CLAIM

The ornamental design for a glove with reduced fingertip regions and a tear indicator rolled cuff, as shown and described.

DESCRIPTION

FIG. 1 is a front elevational view of a hand-specific glove with reduced fingertip regions and a tear indicator rolled cuff in accordance with our design, where the glove is designed to be worn on the left hand of a user; a glove for a right hand of the user being a mirror-image thereof;
FIG. 2 is a rear elevation view thereof;
FIG. 3 is a left side elevation view thereof;
FIG. 4 is a right side elevation view thereof;
FIG. 5 is a top plan view thereof;
FIG. 6 is a bottom plan view thereof; and,
FIG. 7 is a longitudinal cross-section of a middle finger region taken along line 7-7 of FIG. 2.
The broken lines illustrate environment and form no part of the claimed design.
